UNITED STATES PATENT OFFICE

96,723

DESIGN FOR A HINGE FOR TOILET SEATS AND COVERS

Vernon W. Campbell, Nashua, N. H., assignor to
C. F. Church Mfg. Co., Willimansett, Mass., a
corporation of Massachusetts

Application June 10, 1935, Serial No. 57,217

Term of patent 14 years

To all whom it may concern:

Be it known that I, Vernon W. Campbell, a citizen of the United States, residing at Nashua, in the county of Hillsboro and State of New Hampshire, have invented a new, original, and ornamental Design for a Hinge for Toilet Seats and Covers, of which the following is a specification, reference being had to the accompanying drawing, forming a part thereof.

Fig. 1 is a perspective view as seen from the rear and left of a hinge for toilet seats and covers showing my new design;

Fig. 2 is a front elevation of the same;

Fig. 3 is a sectional elevation of the same looking toward the right-hand hinge post of Fig. 1 and shows the merging together of the contours of the upper and lower arms into the approximate form of a semicircle; and

Fig. 4 is an end elevation as seen from the left of Fig. 1.

I claim:

The ornamental design for a hinge for toilet seats and covers, substantially as shown and described.

VERNON W. CAMPBELL.
